APPARATUS FOR REFINING LIQUIDS

Rudolph C. Osterstrom, Chicago, Ill., and Robert T. Tucker, Muskogee, Okla., assignors to The Pure Oil Company, Chicago, Ill., a corporation of Ohio

Application September 12, 1927
Serial No. 218,958

1 Claim. (Cl. 37—12)

The present invention relates to improvements in processes of refining liquids.

The present invention is applicable to many arts, as for example the treatment of hydrocarbons, fats, waxes, sugar solutions, molasses, beverages, paints, varnish, turpentine, and the like. For convenience of description, the present invention will be described with particular reference to the refining of oils, though it will be understood that the invention is not limited to the treatment of oils.

According to prior practice and referring more particularly to hydrocarbon oils, oils have been refined by acid treatment or other treatments, which treatments have been supplemented by treatment with refining agents such for example as charcoal, bone ash, fuller's earth, acid treated clays, bentonite and other agents, which agents have had the function of bleaching or de-colorizing the oil. The present invention relates to oils or other liquids which have been preliminarily treated or those which have not been preliminarily treated, and has for one of its objects the provision of a process for increasing the efficiency of the refining agent, as above referred to.

A further object is to provide an improved process for refining liquids in which the refining agent is thoroughly impregnated with the liquid under treatment, whereby the refining qualities of the refining agent are utilized to the maximum extent.

A further object is to provide an improved process of refining liquids in which the amount of liquid which may be refined from a given amount of refining agent is increased over prior practice; or, expressed in other language, in which the amount of refining agent which need be used per unit volume of liquid is decreased from prior practice.

A further object is to provide an improved process in which the contacting step wherein the liquid and the refining agent are brought into intimate contact with one another is accomplished under such conditions that thorough impregnation of the refining agent by the liquid under treatment is accomplished.

Further objects will appear as the description proceeds.

The one figure of the drawing indicates diagrammatically a system by means of which the present invention may be carried out.

Referring to the drawing, the numeral 1 indicates a storage tank for liquid to be treated. This liquid may be oil which has been previously acid treated, or it may be untreated oil or other liquid. Connected to the tank 1 is the pipe line 2 controlled by the valve 3. Said pipe line 2 leads to the pump 4, the discharge side of which

is connected to the pipe 5. The pipe 5 is connected by any suitable connection to two pipe lines 6 and 7, of which the pipe line 6 leads to the top of the mixing tank 8 and of which the pipe line 7 leads to a coil 8a, which forms one bank, preferably the lower bank, of coils of a heater 9. The pipe line 6 is controlled by a pair of valves 10 and 11. Between said valves 10 and 11 is a pipe line 12 leading from the pipe line 6 to the lower portion of the mixing tank 8. Said pipe line 12 is controlled by means of the valve 13. The pipe line 7 at a point between the connection to the pipe line 6 and the coil 8a is provided with a valve 13a.

The numeral 14 indicates a blow case which may be charged with the comminuted solid absorbent refining agent to be used, such for example as charcoal, bone ash, fuller's earth, acid treated clays, bentonite, or any of the other refining agents known to those skilled in this art. Such agent may be charged through the port 15, which may be closed by any suitable air-tight closure. An air line 16 communicates with the upper portion of the blow case 14, whereby air under pressure may be communicated to said blow case. Said blow case is connected, by means of the pipe 17, to the upper region of the mixing tank 8. The oil pipe line 6 and the refining agent pipe 17 may lead to a common nozzle or to adjacent nozzles, whereby oil from the tank 1 and refining agent from the blow case 14 may be intimately mixed in the upper portion of the mixing tank 8. Communicating with the bottom of the mixing tank 8 and the pipe line 2 between the valve 3 and the pump 4 is the pipe line 17a, which is controlled by the valve 17b.

The side of the heating coil 8a opposite to the pipe line 7 communicates through the pipe line 18 to the evaporator 19. Moisture, light oils and other diluents may be evaporated off in the evaporator 19, such products passing through the line 20 to the condenser 21, from which they may be conducted through the pipe 22 to any convenient storage tank. The lower region of the evaporator 19 has communication through the pipe line 23 to the suction side of the pump 24. The discharge side of the pump 24 is connected through the pipe line 25 to the lower extremity of the upper bank of coils 26 in the heater 9. The upper extremity of the bank of coils 26 communicates with the pipe line 27, which leads to the cooling box 28, whence the oil passes through the pipe 29 to the receiving tank 30. A pressure reduction valve may be positioned in line 27 or 115 in line 29 and is indicated at 27a. The discharge side of the receiving tank 30 communicates through the pipe 31 with the pump 32, which delivers treated oil through the pipe 32a to the filter press 33. The oil, after having been filtered 120

in the filter press 33, passes through the pipe 34 to the storage tank 35. The process which constitutes the present invention may be carried out by the apparatus above described in substantially the following manner. A supply of oil or other liquid to be treated is maintained in the storage tank 1, which oil or other liquid may be untreated oil or other liquid or may be liquid which has been partly treated to refine same, as for example by an acid treatment, an alkali treatment, or any equivalent treatment. Oil will be charged into the mixing tank 8 by pumping same, by means of the pump 4, through the pipe line 2 and pipe line 6, the valves 3, 10 and 11 being open at this time and valves 13, 13a and 17b being closed. When sufficient oil has been charged into the mixing tank 8, the valve 3 will be closed and the valve 17b will be opened. The pump 4 will now circulate oil in the mixing tank 8 through the line 17a, valve 17b, pump 4 and pipe line 6. While this recirculating process is being carried on, refining agent will be blown from the blow case 14 through the pipe 17 into the upper region of the mixing tank 8, whereby an intimate mixture of oil and refining agent will be accomplished. No novelty is claimed in this application for the mixture of the refining agent with the oil in the mixing tank 8. After sufficient intermixture of oil and refining agent has been accomplished oil is delivered from the mixing tank 8 to the coils of the heater 9. For this purpose valve 11 is closed, valve 10 is throttled down and valves 13 and 13a are opened. Air is shut off from the air line 16, so that no more refining agent is blown into the mixing tank 8. The pump 4 now draws the mixture of oil and refining agent from the lower portion of the mixing tank 8 through the pipe line 17a and valve 17b and delivers said oil at a superatmospheric pressure through the line 5, valve 13a and pipe line 7 to the lower bank of coils 8a in the heater 9. From the bank of coils 8a the heated oil is delivered to the evaporator 19, which may be externally heated to drive off relatively light constituents such as water moisture or diluents. By reason of the fact that pressure is communicated to the lower region of the mixing tank 8 through the pipe 12, the mixture of liquid and refining agent is kept in agitation within the tank 8, whereby the refining agent is maintained in suspension. The oil from the evaporator 19 passes through the pipe 23 to the pump 24, which puts said oil under superatmospheric pressure which in a practical embodiment of the present invention may be as high as 300 pounds per square inch. The pressure impressed upon the oil by the pump 24 may be chosen to suit individual conditions, such for example as the fineness of the refining agent, the viscosity of the liquid being treated, the temperature of the oil, and other conditions. The oil under pressure is delivered to the bank of coils 26 in the heater 9. The temperature within the coil 26 will be chosen to suit conditions, a temperature in the neighborhood of 350 degrees F. having been shown to be satisfactory in some instances. This temperature may range from atmospheric temperature up to 500 degrees F. or higher. The correlation of temperature and pressure within the bank of coils 26 will be such that the refining agent will be thoroughly impregnated, whereby to utilize the refining qualities to the greatest possible extent. It will be understood without explanation that the more viscous liquids will require a higher temperature and higher pressure, whereas the

less viscous liquids may be treated at a lower temperature and lower pressure. The ordinary skilled worker in the art may of course readily determine the proper temperatures and pressures to be used for the particular liquid under treatment. The lower limit of pressure to be used will be the pressure necessary to impregnate the particular refining agent with the particular liquid being treated at the temperature being used. Ordinarily it will be more economical to use the higher temperatures, inasmuch as the pressures necessary will be less at the higher temperatures than at the lower temperatures. With such agents and liquids as have come within the observation of applicants in their practice of the present invention the minimum pressure to accomplish complete impregnation at the higher temperatures has been in the neighborhood of 60 pounds per square inch, though incomplete impregnation may be accomplished at less pressures. 95

After a complete impregnation has occurred in the bank of coils 26 in the heater 9, the treated oil passes through the cooling box 28 into the receiving tank 30, whence it may be treated in any preferred manner to remove the suspended particles. According to the drawing, the oil is passed from the receiving tank 30 through a filter press 33 for this purpose, the filtered treated oil being delivered to the storage tank 35. 100

The present invention should be distinguished from any process in which it is attempted to impregnate the refining agent with the liquid to be treated by prolonging the soaking under atmospheric pressure or pressures slightly above atmospheric pressure. The pressure involved, in order to realize the benefits of the present invention, must be sufficient to force the liquid into the cellular structure of the refining agent, breaking down the tissues of said refining agent if necessary. 105

It will be obvious that the process may be varied in a number of particulars from the one which was chosen for the above description. Moreover, the apparatus may be changed without departing from the process which constitutes the present invention. For example, the refining agent, instead of being blown into contact with the oil to be treated, may be mixed with said oil in any other preferred manner. Moreover, if preferred, the bank of coils 8a for 120 preliminarily heating the oil may be omitted. It is intended to cover all modifications of the present invention so long as they fall within the scope of the appended claim. 110

What is claimed is—

In an apparatus for refining petroleum oils, the combination of a heater, means for mixing a cellular refining agent with a petroleum oil, pump and conduit means for conveying the mixture from said mixing means to said heater, a 135 vaporizing chamber, conduit means connecting said heater with said vaporizing chamber, means for heating a flowing stream of liquid, pump and conduit means connecting the lower portion of said vaporizing chamber with said last 140 named heating means, said pump being adapted to pass a liquid mixture under pressure through said means for heating a flowing stream of liquid, and means operably connected to said last named heating means for separating the refin- 145 ing agent from the petroleum oil.
